DAVID E. ROSE AND HARRY E. HOSSFELD, OF TOPEKA, KANSAS.

TRUNK.

1,413,062.

Specification of Letters Patent. Patented Apr. 18, 1922.

Application filed March 13, 1919. Serial No. 282,470.

To all whom it may concern:

Be it known that we, DAVID E. ROSE and HARRY E. HOSSFELD, citizens of the United States of America, residing at Topeka, in the county of Shawnee, State of Kansas, have invented certain new and useful Improvements in Trunks, of which the following is a specification.

This invention relates to improvements in trunks of the character known as wardrobe trunks and has for its prime object the provision of a trunk comprising a tray for holding wearing apparel or other articles which, with the trunk standing on end and open, may be swung into horizontal position and thus retained for convenience in packing or unpacking.

Other objects and advantages will become apparent upon consideration of the following portions of the specification and the appended claims.

A perspective of the trunk, positioned on end and opened, is shown in the annexed drawing, the tray above mentioned being disposed horizontally and supported by a latch.

The body of the trunk is formed in two (2) sections A—B which are hingedly connected along line C and provided with conventional interlocking members D—E. Section A is provided with a hinged lid F which fits over both of said sections when the latter are brought together and thus forms one end of the trunk, said lid having a hasp G provided with spring pressed bolts H which engage a conventional fixture (not shown) carried by the hinged portion J of section B so that the trunk may be locked when said sections are brought together. Section B is spanned by a metal brace K which is engaged by the hooked extremity of weighted latch L pivotally affixed at M to one side of tray N when the latter is brought into horizontal position by simply lowering hinged element J to which said tray is riveted or otherwise fastened. If preferred, tray N may be pivotally suspended between those portions of the side walls of section B denoted by J¹ and in such event element J is not fastened to said tray, but serves simply to admit of the latter being raised from a vertical to a horizontal position.

An additional lock of conventional type, comprising elements O and P, may be employed to retain the sections together when the trunk is closed, but it is obvious that locks of special construction may be used for the same purpose without affecting the

above described invention and it will be understood that the interior of section A may, in practice, be fitted with garment hangers or 60 other conventional equipment of so-called wardrobe trunks.

Having thus fully described our invention, what we claim as new and desire to secure by Letters Patent is:—

1. A trunk comprising hingedly connected sections, a tray fitting within said sections, and a hinged panel forming a part of the side walls and floor of one of said sections secured to said tray, whereby the latter may 70 be raised from a vertical to a horizontal position when the trunk is stood upon end.

2. A trunk comprising hingedly connected sections, a tray fitting within said sections, a hinged panel forming a part of the side 75 walls and floor of one of said sections secured to said tray, whereby the latter may be raised from a vertical to a horizontal position when the trunk is stood upon end, and means for retaining said tray in horizontal 80 position.

3. A trunk comprising hingedly connected sections, a tray fitting within said sections, a latch secured to said tray, a hinged panel forming a part of the side walls and floor 85 of one of said sections secured to said tray, whereby the latter may be raised from a vertical to a horizontal position when the trunk is stood upon end, and a member adapted to engage said latch for the support of said 90 tray in horizontal position.

4. A trunk comprising hingedly connected sections, a lid carried by one of said sections adapted to engage the other thereof, and a hinged panel forming a part of the 95 side walls and floor of one of said sections adapted to swing outwardly when the trunk is stood upon end and opened, said panel being disposed immediately adjacent to said lid when the trunk is closed.

5. A trunk comprising hingedly connected sections, a lid carried by one of said sections adapted to engage the other thereof, and a hinged panel forming a part of the 105 floor of one of said sections adapted to swing outwardly when the trunk is stood upon end and opened, said panel being disposed immediately adjacent to said lid when the trunk is closed.

DAVID E. ROSE.
HARRY E. HOSSFELD.
